DESIGN FOR A SHAVING BRUSH

Paul S. Paulsen, Sr., Belleville, Mich.

Application July 7, 1948, Serial No. 147,414

Term of patent 3½ years

(Cl. D9—2)

To all whom it may concern:

Be it known that I, Paul S. Paulsen, Sr., a citizen of the United States of America, residing at Belleville, in the county of Wayne and State of Michigan, have invented a new, original, and ornamental Design for a Shaving Brush, of which the following is a specification, reference being had to the accompanying drawing, forming a part thereof, wherein:

I claim:

The ornamental design for a shaving brush, as shown.

PAUL S. PAULSEN, SR.
